UNITED STATES PATENT OFFICE.

ARTHUR C. BRENCKLE AND WALTER A. ANGER, OF MILWAUKEE,
WISCONSIN.

BOX-FASTENER.

SPECIFICATION forming part of Letters Patent No. 693,489, dated February 18, 1902.

Application filed April 15, 1901. Serial No. 55,841. (No model.)

To all whom it may concern.

Be it known that we, ARTHUR C. BRENCKLE and WALTER A. ANGER, citizens of the United States, and residents of Milwaukee, in the county of Milwaukee and State of Wisconsin, have invented certain new and useful Improvements in Box-Fastening Devices; and we do hereby declare that the following is a full, clear, and exact description thereof.

Our invention has especial reference to fastenings designed for boxes containing bottled goods, though not necessarily confined thereto; and it consists in certain peculiarities of construction and combination of parts, as will be fully set forth hereinafter in connection with the accompanying drawings and subsequently claimed.

In the said drawings, Figure 1 is a transverse vertical sectional view through a box equipped with our said invention, taken on the line 1 1 of Fig. 2; and Fig. 2 is a longitudinal vertical sectional view through such box, taken on the line 2 2 of Fig. 1.

Referring to the drawings, A represents the box, and B the cover thereof, hinged, as shown at b, to the top of the box and designed to come flush with the vertical walls of the said box. The front wall of the box is formed with an opening or hand-hole c therein of sufficient size to admit the passage therethrough of one's fingers.

C is a block secured to the front inner surface of the cover B, so as to be adjacent to the opening c when the cover is closed, and D is a catch secured to and depending from said block, this catch in its preferred form consisting of a doubled strap of metal constituting a vertically-arranged loop, and it is obvious that, if preferred, the said catch may be secured directly to the cover itself instead of to the block C, as shown.

E is a latch having a spring-shank e, whose lower end is secured to the inner side of the front wall of the box, as by the clenched nails f f or by screws or otherwise, the latch E engaging with the aforesaid catch D, as shown, this latch having a transverse perforation g therethrough, which when the latch and catch are in engagement is in line with perforations d d in the said catch D.

F is a seal of ordinary construction con-

nected to a wire h, which wire is passed through the perforations d g d in the catch and latch and then secured to the seal, so that when once secured the box cannot be opened without breaking the seal or the box itself, thus guarding against tampering with the box or its contents. The seal can be readily reached to be cut by the recipient of the goods through the opening c, and similarly when the box is closed the seal can be adjusted through said opening, and after the seal is removed the latch and catch will operate as before, one great advantage lying in the fact that the fastening is always within the box itself, and to unlatch the device it is only necessary to push a finger through the opening c against the latch-shank e, while the latching of the device is automatic on the closing of the cover B, as the catch D will slide down over the inclined front edge of the latch E and push it back till the base of the catch D comes below the base of the latch E, when the spring-shank e will force the latch forward to the position shown in Fig. 1, thus completing the engagement of the latch and catch. Hence with our device the cover will always stay shut in latch engagement with the catch when the box is closed.

Our device is extremely simple and very economical in manufacture and can be readily applied to existing boxes as well as to new ones, and boxes fitted with our fastening device may be packed very closely together, as the said fasteners are always within the boxes, which is an additional measure of safety in transportation.

Having thus described our invention, what we claim as new, and desire to secure by Letters Patent, is—

1. The combination with a box having a hinged cover, and a hand-hole in its front wall, of a catch secured to and depending from said cover back of said hand-hole, a spring-latch secured within said box and in engagement with said catch, the latter and the latch having transverse registering holes therethrough, and a wire seal passed through said registering openings, the latch, catch, and seal being all within the box, but accessible through the hand-hole in the front wall of the latter.

2. The combination with a box, having a cover hinged to the rear wall thereof, and the front wall of said box being formed with a wholly - open hand - hole extending there-
5 through, of a doubled metallic strap, forming an open-loop catch, secured to and projecting vertically from the said cover, at a point back of said front wall, and the said loop-straps having transverse perforations therethrough;
10 a latch comprising a beveled head with a transverse perforation therethrough, and a spring-shank secured to the inner side of the front wall of the box and projecting upward and backward for engagement with said loop-

catch, and a wire seal passed through the reg- 15 istering transverse openings in the loop-straps and latch-head, the latch, catch and seal being all within the box, back of the hand-hole, but accessible therethrough.

In testimony that we claim the foregoing 20 we have hereunto set our hands, at Milwaukee, in the county of Milwaukee and State of Wisconsin, in the presence of two witnesses.

ARTHUR C. BRENCKLE.
WALTER A. ANGER.
